BOOM LOCKING APPARATUS FOR A BACK HOE

John P. Waite, Milwaukee, Wis., assignor to J. P. Waite, Inc., Milwaukee, Wis., a corporation of Wisconsin

Application July 5, 1955, Serial No. 519,986

4 Claims. (Cl. 214—138)

This invention relates to power operated construction apparatus, such as a back hoe or the like, and more particularly to an apparatus for locking a boom in position with respect to the supporting structure.

The conventional back hoe includes a boom which is pivotally secured to the cab or supporting structure of the hoe. A dipper which is adapted to penetrate the material to be excavated is connected through a dipper stick to the outer end of the boom. The boom is adapted to be raised and lowered and the dipper is pivoted with respect to the boom to provide a digging and dumping action for the dipper.

If during digging, the dipper encounters a hard material which is difficult to penetrate, the boom tends to pivot upwardly rather than the dipper digging into the material because the combined weight of the dipper and the boom is not sufficient to cause penetration of the hard material by the dipper.

The present invention is directed to an apparatus associated with the boom for bringing the weight of the cab or supporting structure to bear on the dipper to increase the force of penetration of the dipper into the material to be excavated. According to the invention a closed hydraulic system is provided which includes a cylinder having a ram freely slideable therein and a conduit which provides communication between the opposite ends of the cylinder. The cylinder is connected to either the boom or supporting structure and the ram is connected to the other. As the boom is pivoted with respect to the supporting structure, the ram is moved within the cylinder and the fluid flows through the system with the fluid being displaced from one end of the cylinder and passing through the conduit to the other end of the cylinder.

To lock the boom with respect to the supporting structure a valve is provided in the conduit and by closing the valve the flow of fluid through the closed system is cut off. This prevents the movement of the ram within the cylinder and locks the boom with respect to the supporting structure. With the boom locked in position with respect to the supporting member the boom and supporting member are in effect an integral structure and the weight of the supporting member is brought to bear on the dipper as the dipper penetrates into the material to be excavated. This tends to prevent the boom from pivoting upwardly or raising when the dipper encounters hard materials.

The present invention provides a simple and inexpensive means of bringing the weight of the supporting structure to bear on the boom to increase the force exerted during digging. The apparatus of this invention can be readily adapted to conventional back hoe or crane constructions without any major alterations of the parts or elements of the hoe.

The drawings illustrate the best mode presently contemplated of carrying out the present invention.

2

In the drawings:

Figure 1 is a diagrammatic side elevation of a back hoe employing the present invention;

Fig. 2 is a fragmentary enlarged side elevation with parts broken away in section and showing the hydraulic system for locking the boom in position with relation to the supporting structure;

Fig. 3 is a view similar to Fig. 2 with the boom being in a lowered position; and

Fig. 4 is a top plan view of the structure shown in Fig. 2.

The drawings illustrate a power operated back hoe or drag shovel having a cab 1 which houses the drive mechanism and is rotatable on crawlers or treads 2.

A boom 3 is pivotally connected to a pair of lugs 4 which extend upwardly from the floor of the cab. A dipper stick 5 is pivotally secured to the outer end of the boom 3 and the dipper stick carries a dipper 6 which is adapted to penetrate and dig into the material to be excavated.

The dipper 6 and dipper stick 5 are pivoted about boom 3 by a cable 7 which is secured to cable drum 8. Cable 7 passes over sheaves 9 and 10, which are secured to boom 3, and sheave 11 which is secured to the forward edge of the dipper. The cable 7 is dead-ended on the boom as indicated by 12. With this sheaving arrangement the dipper is drawn inwardly toward the boom as cable 7 is retrieved and moves away from the boom as the cable 7 is let out.

The boom 3 is raised and lowered by a conventional sheaving arrangement in which a cable 13, which is secured to cable drum 14, passes over sheaves 15 and 16 and is dead-ended on arms 17 which are pivotally attached to the upper end of dipper stick 5 and supports the sheave 16. Sheave 15 is rotatably secured to braces 18 which extend upwardly from cab 1. By retrieving cable 13, sheave 16 is moved toward sheave 15 thereby pivoting boom 3 upwardly about the forward portion of the cab, while letting out cable 13 serves to pivot boom 3 downwardly with respect to the cab 1.

During the digging operation the dipper 6 may frequently encounter hard materials, which are difficult to penetrate, and the boom thereby tends to pivot upwardly rather than the dipper digging into the material because the combined weight of the boom and dipper is not sufficient to cause penetration of the material by the dipper. To overcome this difficulty, means are provided to prevent pivotal movement of the boom with respect to the cab or supporting structure so that the weight of the cab 1 and machinery and treads 2 will be brought to bear on the dipper to thereby increase the force of penetration exerted by the dipper. This is accomplished by pivotally attaching a cylinder or reservoir 19 to a pair of lugs 20 which extend upwardly from the floor of the cab. Cylinder 19 is adapted to contain a hydraulic fluid, and a piston 21 is slidably disposed within the cylinder. The piston 21 is attached to the central portion of a rod 22 which extends through aligned openings in the ends of the cylinder and the upper end of rod 22 is pivotally connected to a pair of arms 23 which extend outwardly from the inner end of boom 3. As the lower end of rod 22, extending downwardly beyond the piston 21, is approximately equal to the length of the upper portion of the rod extending upwardly beyond the piston, the effective volume of the cylinder on either side of the piston, when the piston is in the center of the cylinder, is the same.

To provide a closed hydraulic system for the hydraulic fluid, a conduit 24 is connected between fittings 25 and 26 which are secured within openings in the opposite end portions of cylinder 19. The conduit 24 estab-

lishes communication between the opposite ends of the cylinder, and as the boom 3 is pivoted with respect to the cab 1, the piston 21 moves within the cylinder to discharge fluid from one end of the cylinder through conduit 24 to the opposite end of the cylinder.

For example, as the boom 3 is lowered or pivoted downwardly with respect to the cab, the piston 21 is moved upwardly, thereby forcing fluid from the upper end of cylinder 19 downwardly through conduit 24 to the lower end of the cylinder. When the boom 3 is raised, the piston 21 moves downwardly within cylinder 19 forcing fluid from the lower end of the cylinder through conduit 24 to the upper end thereof. Due to the fact that the piston rod extends through both ends of cylinder 19, the volume of fluid displaced from one end is equal to the increased volume available for fluid at the other end of the cylinder and thus the piston can travel to the ends of the cylinder without interference.

To cut off the flow of fluid within the closed hydraulic system and thereby prevent relative pivotal movement between the boom 3 and cab 1, a valve 27 is disposed in the conduit 24. Valve 27 may either be manually or automatically operated and serves to prevent the flow of fluid through the conduit and thereby prevent movement of piston 21 within the cylinder 19.

In operation of the present apparatus the boom 3 is lowered by letting out cable 13 until the dipper has been lowered to the desired position. The valve 27 is then closed to prevent flow of fluid through the closed hydraulic system and thereby prevent relative pivotal movement between the boom 3 and the cab 1. The dipper is then actuated by retrieving cable 7 and penetrates into the material to be excavated. If the dipper engages hard material, the weight of the dipper 6, boom 3, cab 1 and treads 2 will be brought to bear on the dipper to increase the force of penetration. This added weight, which in effect acts through the dipper, tends to prevent the boom from pivoting upwardly and will increase the digging force of the apparatus.

While the present description is directed to the cylinder 19 being connected to the cab 1 and piston rod 22 connected to the boom 3, it is contemplated that the cylinder can be connected to the boom and the piston rod to the supporting structure. Similarly, the cylinder and piston rod could interconnect the supporting structure and the lower surface of the boom. In this event, the action of the piston rod would be opposite to that described above.

The present invention provides a simple apparatus for increasing the force exerted by the dipper during digging. The apparatus may readily be adapted for use with convention-type back hoes, cranes, or other apparatus having a boom which pivots relative to the supporting structure.

Various modes of carrying out the invention are contemplated as within the scope of the following claims particularly pointing out and distinctly claiming the subject matter which is regarded as the invention.

I claim:

1. In a power operated back hoe, a supporting structure, a boom pivotally attached to the supporting structure and adapted to carry a dipper, a cylinder to contain a hydraulic fluid and pivotally connected to the supporting structure, a piston freely slidable within said cylinder, a piston rod secured to the piston and extending through opposite ends of the cylinder and having one end thereof pivotally connected to the boom, a conduit extending externally of the cylinder providing communication between the ends of the cylinder with the fluid being displaced from one end of the cylinder by said piston and being free to pass through the conduit to the other end of the cylinder as the piston moves within the cylinder, separate means for pivoting the

boom with respect to the supporting structure with the piston being moved within the cylinder as the boom is pivoted, and valve means disposed in the conduit to shut off the flow of fluid therethrough and lock the boom in a given position with respect to the supporting structure and bring the weight of the supporting structure to bear on the dipper as said dipper penetrates into the material to be excavated.

2. In a power operated apparatus, a supporting member, a boom member pivotally attached to said supporting member, a closed hydraulic system including a reservoir connected to one of said members and conduit means providing communication between opposite end portions of said reservoir, a hydraulic fluid disposed within said reservoir, a piston rod disposed through aligned openings in opposite ends of said reservoir and connected to the other of said members, a piston secured to the central portion of said rod and slidable within said reservoir, separate means for pivoting the boom member with respect to the supporting member with said piston adapted to move within said reservoir in accordance with pivotal movement of said boom member and displace a quantity of said fluid from one end portion of said reservoir through said conduit means to the other end portion of said reservoir, and means associated with said hydraulic system for cutting off the flow of said fluid through said system to lock the boom member with respect to said supporting member and prevent pivotal movement therebetween.

3. In a power operated excavator, a plurality of longitudinally spaced ground supports, a frame structure supported by said ground supports, a boom structure pivotally connected to the frame structure for movement in a vertical plane, a digging implement pivotally connected to the boom structure for movement in a vertical plane and for ground contact forwardly of the ground supports, power means to pivot the boom structure, power means to pivot the digging implement, a cylinder containing a fluid and pivotally connected to one of said structures, a piston freely slidable within said cylinder, a piston rod connected to the piston and extending through an end of the cylinder and having the outer end thereof pivotally connected to the other of said structures, conducting means providing communication between the opposite end portions of said cylinder with the fluid being free to flow from one end portion of the cylinder through said conducting means to the opposite end portion of the cylinder as the piston moves within the cylinder, said cylinder and said piston being separated from said first named power means and said piston being adapted to move relative to the cylinder as the boom structure is pivoted by said first named power means, and normally open valve means associated with said conducting means to normally permit free flow of fluid through said conducting means during pivotal movement of said boom structure and to restrict the flow of fluid through said conducting means when closed and lock the boom structure with respect to the frame structure and prevent pivotal movement therebetween, whereby when the digging implement is pivoted relative to the boom structure to produce an upward reaction of the ground on the digging implement, such pivoting will tend to elevate the boom structure and the forward ground supports to transfer weight from said forward ground supports to the digging implement.

4. In a power operated excavator, a supporting structure, a boom structure pivotally connected to the supporting structure for movement in a vertical plane, a digging implement pivotally connected to the boom structure for movement in a vertical plane, power means for pivoting the boom structure and for pivoting the digging implement, a hydraulic system separate from said power means and including a cylinder containing a hydraulic fluid and a piston freely slidable within said cylinder and having a piston rod extending through an end of said

cylinder, said cylinder being pivotally connected to one of said structures and said piston rod being pivotally connected to the other of said structures, and said hydraulic system having conducting means providing communication between opposite end portions of said cylinder with the fluid being free to flow from one end portion of the cylinder through said conducting means to the opposite end portion of the cylinder as the piston moves within the cylinder, said piston being adapted to move relative to the cylinder as the boom structure is pivoted, valve means associated with said conducting means to restrict the flow of fluid therethrough and lock the boom structure with respect to the supporting structure and prevent pivotal movement therebetween, and means associated with the hydraulic system to compensate for the volumetric displacement of the piston rod in the cylinder, where-

by the amount of hydraulic fluid leaving one end of the cylinder bears the same relation to the amount of fluid entering the opposite end of the cylinder during movement of said piston within the cylinder as the effective surface area of the piston facing said first end of the cylinder bears to the effective surface area of the piston facing the other end of the cylinder.
